UNITED STATES PATENT OFFICE.

ELLIS J. G. PHILLIPS, OF AURORA, ILLINOIS, ASSIGNOR TO RICHARDS-WILCOX MANUFACTURING COMPANY, OF AURORA, ILLINOIS, A CORPORATION OF ILLINOIS.

MEANS FOR SUPPORTING TROLLEY-TRACKS.

1,167,656.

Specification of Letters Patent. Patented Jan. 11, 1916.

Application filed May 17, 1915. Serial No. 28,649.

To all whom it may concern:

Be it known that I, ELLIS J. G. PHILLIPS, a citizen of the United States, residing at Aurora, in the county of Kane and State of Illinois, have invented certain new and useful Improvements in Means for Supporting Trolley-Tracks, of which the following is a specification, reference being had to the accompanying drawings.

- 10 In some buildings having wide doorways that are closed by one or more large and heavy doors suspended by trolleys from an overhead track, it is not feasible to uncover the doorway by moving the door or doors in 15 a straight line parallel with the wall in which the doorway is formed. To permit a trolley-hung door to be moved back close to and substantially parallel with a wall that is at right-angles to the wall in which the doorway is formed, there have been provided 20 two trolley-tracks at right-angles to each other, one secured over the doorway and the other secured to the side wall toward which the door is to be moved, a trolley or wheeled 25 frame running on each of said tracks, and the pendants or rods that connect the trolleys or wheeled frames with the door having a suitable swiveled connection with one or the other of said parts to permit the required 30 turning movement of the door to bring it to the required open or closed position. In such an arrangement of the parts, however, it was deemed necessary to have the track that was secured to the side wall higher up 35 on the wall than the other track and with its end extending over the adjacent end portion of such other track. Such arrangement has been objectionable for two reasons, viz: it made necessary, of course, a longer pendant or rod for connecting the door with the trolley that ran on that higher track than 40 was employed between the door and the trolley on the other track, and in order to have the door, when in closed position, come 45 snugly against the door jambs it was necessary to cut an opening in the track that extends over the doorway, into which opening the pendant of the hanger on the other track might enter,—for, of course, the pendant or rod of one trolley must always lie 50 substantially in line with the longitudinal center of the other trolley in order that the door may come snugly against the door jambs in closed position or close to the side wall when in open position.

It is the object of this invention to provide improved means for supporting trolley-tracks arranged at an angle and to overcome the objections above noted. To that end, I have provided an improved joint-bracket adapted to receive the adjacent ends of the two tracks that are arranged at an angle to each other whereby said tracks will be in the same horizontal plane, thus making it unnecessary to make one pendant or rod 65 longer than the other.

It is a further object to so construct such bracket as to permit one of the trolleys to extend into the bracket, at the limit of movement in one direction of the door, sufficiently far to cause its pendant or rod to be in line with the longitudinal center of the other trolley, thus insuring the door being caused to lie very close to the side wall when the door is fully opened and to the jambs of 70 the doorway when such door is closed.

These objects I attain by the means shown in the drawings and hereinafter particularly described.

In the drawings,—Figures 1 and 2 are 80 bottom and top views, respectively, of the improved bracket; Fig. 3 is a vertical section taken at line 3—3 of Fig. 2; Fig. 4 is an end view of the bracket with two pieces of track of well-known form supported 85 therein, one of such pieces of track being shown in section; Fig. 5 is a horizontal section through the bracket and two pieces of track supported by it, the section being taken at line 5—5 of Fig. 4; Fig. 6 is a plan view 90 of the bracket and the two tracks supported thereby as arranged for use in a building, and showing a door partially opened, such door being supported by trolleys running on the tracks; Fig. 7 is a perspective view of 95 the parts shown in Fig. 6, but showing the door completely opened and turned against the side wall of the building; and Fig. 8 is a detail, being an enlarged vertical section taken at line 8—8 of Fig. 7 and showing the 100 swiveled connection of the hanger-rod with the trolley or wheeled frame, and the projection of one of the extensions of the bracket into a socket in one of the building walls.

As shown in the drawings, the bracket, 105 which is best made as a single casting, comprises two track-supporting members indicated, respectively, by 10 and 11, said members being the same in size, shape and form and each adapted to receive and hold 110

one end of a piece of trolley-track, the two pieces of track shown being of a well-known shape and formed from a single piece of sheet-metal, whereby is provided a top wall, side walls and a slotted bottom. These two pieces of track are indicated by *a* and *b*, respectively, and for convenience track *a* will be considered as the one arranged over the doorway and track *b* as the one arranged at an angle thereto against a side wall. The bracket also comprises two extensions 12 and 13 in line, respectively, with the track-supporting members 10 and 11, and each projecting a considerable distance beyond the plane of one of the inner sides of the bracket,—by "inner sides" being meant those sides that lie against the supporting walls of a building when the bracket is secured in place in a corner, as shown in Figs. 6 and 7. These extensions are each shown as having their upper and lower walls rounded, which produces an end conforming approximately to the trolley-wheels that enter the extensions, and thereby make a more perfect abutment or stop, as hereinafter described. Each abutment is shown as having an opening in its outer end, but such opening has no function in connection with the operation of the door, but is made to facilitate the operation of casting the bracket. So far as concerns the use of the bracket, it may, therefore, be considered as having a closed end.

In the bottom of each track-supporting member is a centrally-located slot,—that in the member 10 being indicated by 14 and that in the member 11 by 15. These slots communicate with each other at their inner ends, as clearly shown in Figs. 1 and 5, thus forming a continuous right-angled slot from the outer end of the member 10 to the outer end of the member 11. These slots correspond in width to that of the slots in the pieces of track supported by the bracket. As clearly shown, the walls of that portion of the members 10 and 11 that receives the track pieces *a* and *b* are diminished in thickness to an amount substantially equal to the thickness of the metal of the track, and thereby an interior shoulder is formed against which the ends of the tracks abut. Furthermore, as will be seen by reference to Fig. 8, this construction causes the inner face of the bottom of the bracket beyond the shoulder to be substantially in the same plane as the upper faces of the track-rails proper, and hence the forward trolley-wheels pass over the track-rail ends with but little, if any, jar.

60 16 indicates suitable lugs through which screws or bolts are to be passed for attaching the bracket as a whole to the walls of a building.

In use my improved bracket will be secured in place in the angle of two walls, as

shown in Figs. 6 and 7, with an end of each track-section *a* and *b* inserted in the members 10 and 11, respectively, as described, ordinary brackets *c* being employed, as usual, to further support the track. The building 70 wall in which the doorway appears is indicated by *d*, and the side wall against which the door *f* is adapted to be moved is indicated by *e*. Inasmuch as the straight faces of the bracket must rest snugly against the 75 building walls, each of such walls must be recessed or provided with an opening to receive one of the extensions, as clearly shown in Fig. 8 and indicated by dotted lines in Fig. 6.

In use, with my novel bracket secured in the corner of a building as shown in Figs. 6 and 7, and the tracks *a* and *b* secured in place as there shown, a door is to be hung from a trolley or wheeled frame running 85 in each track, and by reason of the swiveling character of the connection between the hanger-rod and the frame of the trolley, as seen in Fig. 8, the trolleys can be moved freely on their respective tracks to open or 90 close the door, as will be clear by an inspection of Fig. 6 where the door is shown as partially opened. In order to have the door lie snugly against the side wall *e*, it is essential that the trolley on the track *a* shall 95 move into the corner bracket until its pendant or rod is in the angle of the slot 14—15. As it reaches this position, the forward wheels will rest on the bottom wall of the extension and will abut against the rounded 100 end wall of the extension 12, which, of course, will arrest the further progress of the trolley. In the closing movement of the door the trolley on track *b* will enter the said corner bracket and its forward wheels 105 will pass into and be stopped by the end wall of the extension 13, at which time its pendant or rod will be in the angle of said slot 14—15, and thereby insure the door 110 being in proper position to close the doorway, for such pendant or rod will then lie directly in line with the longitudinal center of the trolley that runs on the other tracks.

The bracket can be used in either corner of a room at the side of a doorway inasmuch as both track-supporting members and their respective extensions are the same in every respect.

That which I claim as my invention, and desire to secure by Letters Patent, is,—

1. As a new article of manufacture, a joint-bracket for trolley-tracks comprising two track-supporting members at an angle to each other, the bottom wall of each member being slotted for the passage of a door-hanger pendant, and means for permitting the attachment of the bracket to two walls of a building and in the angle formed by such walls.

2. As a new article of manufacture, a

joint-bracket for trolley-tracks comprising two track-supporting members at an angle to each other, each member having a slot in its bottom wall, the two slots opening into each other.

3. As a new article of manufacture, a joint-bracket for trolley-tracks comprising two track-supporting members at an angle to each other and in the same horizontal plane, each of said members having means for permitting the attachment of the bracket to two walls of a building and in the angle formed by such walls.

4. As a new article of manufacture, a joint-bracket for trolley-tracks comprising two track-supporting members at an angle to each other and means for causing the pendant of a trolley entering either member to come to rest opposite the other member.

20 5. As a new article of manufacture, a joint-bracket for trolley-tracks comprising two track-supporting members at an angle to each other, each member having a slot in it for the passage therethrough of a trolley pendant and the two slots opening into each other, and means for causing the pendant of a trolley running on either member to come to rest in the angle formed by the two slots.

6. As a new article of manufacture, a joint-bracket for trolley-tracks comprising two track-supporting members at an angle to each other, each having an extension projecting beyond the plane of the inner side of the other member.

35 7. As a new article of manufacture, a joint-bracket for trolley-tracks comprising two track-supporting members at an angle to each other, each having an extension projecting beyond the plane of the inner side of

the other member, said track-supporting members each having a slot, such slots communicating with each other.

8. As a new article of manufacture, a joint-bracket for trolley-tracks comprising two track-supporting members at an angle to each other, each having an extension beyond the plane of the inner side of the other member, said track-supporting members each having a slot, such slots communicating with each other, and the extensions each having a bottom wall adapted to support the wheels of a trolley.

9. As a new article of manufacture, a joint-bracket for trolley-tracks comprising two track-supporting members at an angle to each other, each member having an extension projecting beyond the plane of the inner side of the other member, said extensions each having a closed end.

10. As a new article of manufacture, a joint-bracket for trolley-tracks comprising two track-supporting members at an angle to each other, each member having an extension projecting beyond the plane of the inner side of the other member, said extensions each having a curved wall closing one end.

11. As a new article of manufacture, a joint-bracket for trolley-tracks comprising two track-supporting members at an angle to each other, the bottom wall of each member being slightly recessed in its outer end portion to form a shoulder whereby the surface of a piece of track placed in said recess will lie substantially flush with the balance of said bottom wall.

ELLIS J. G. PHILLIPS.
